CONTAINER FOR CIGARETTE PACKAGES

Alden K. Crawford, Akron, and Harold G. Arnold,
Wooster, Ohio

Application April 1, 1938, Serial No. 199,490

1 Claim. (Cl. 206—48)

Our invention relates to improvements in containers for cigarette packages and it more especially includes the features pointed out in the annexed claim.

5 The purpose of our invention is to provide a combined container for cigarette packages which includes simple means for attachably and detachably holding a folding booklet for matches; that makes the container a complete and separate entity from a package of cigarettes; that makes the holder collapsible to the extent of the sides and edges folding onto each other for compactness in shipping, etc. or in storing the container in the pocket while awaiting the insertion of a new packet of cigarettes; and that may also provide separate elastic means at the inside corners of the container or depend on the inherent resiliency of the material used to assist in opening up the folded sides and edges.

10 20 25

With these and other ends in view we illustrate in the accompanying drawing such instances of adaptation as will disclose the broad features of our invention without limiting ourselves to the details shown thereon and described herein.

Fig. 1 is a perspective view of a collapsible container with a cigarette package therein.

Fig. 2 is a modification of Fig. 1 in that a separate piece of material is inserted to form a partition between it and the side of the container containing a notched top and bottom so as to separate the folding flap of the match booklet from the cigarette package.

Fig. 3 is a slightly enlarged edge view partly in section.

Fig. 4 is a top elevation of Fig. 3.

Fig. 5 shows elastic inside corner portions.

Fig. 6 shows the container in partially collapsed relation.

40 In the use of our cigarette package container, we may use whatever alternatives or equivalents of structure that the exigencies of varying conditions may demand without departing from the broad spirit of the invention.

45 The container is made up of a notched front, 1, that is structurally an integral part with an edge 5, a back portion 4, and another edge 2, being a continuation of the back 4. The width of this edge 2 gauges the opening of the container. The front 1 is folded over to form the edge 3 which is glued to the edge 2, thus forming an enclosure for a cigarette package which retains its usefulness over a considerable period of time for effective advertising purposes, even

though it may be collapsed while in the user's pocket.

It is not the purpose as has been proposed heretofore to make a folding booklet containing matches so as to become a permanent part of a cigarette package box. We do not make this a structural part of the container and we may simply follow the features shown in Fig. 1. In this the front 1 has an upper and a lower notch 6 formed therein. Each notch has sloping edges 9. The flap 11, 13 and 14 is passed up on the inside of the front 1 so that the permanent fold 15 will be adjacent the bottom notch 6 and the fold 14 will pass out over the top notch and the free end 11 will be tucked under the flap retaining portion 12.

5 10 15 20 25

The modification shown in Fig. 2 includes a separate sheet 8 which may be of thinner material than the body of the container. Its use forms a space between it and the front face 1 to direct the first passage of the flap 11 and the final holding of the flap 13 in place. The folding booklet contains the usual supply of matches 16 and in Fig. 4 the contents of the package 7 is shown by dotted line 17.

25 30 35

In Fig. 5 elastic reinforcements 10 are shown on the inside corners of the container. These may provide a certain amount of resiliency against an absolute breaking down of the corners of the container when it is collapsed.

We may use whatever kind of material that best serves our purpose in the making of the container. It is a complete entity quite independent of a cigarette package or of a folding booklet for matches yet it effectively cooperates with both of these.

40 45 50 55

As the cigarettes are used, whether more frequently than otherwise, there will be a smaller number of cigarettes remaining in the package. It is important that as the package with fewer cigarettes therein becomes compressed in the pocket, the container will not have its usefulness destroyed by being also compressed at about the time the last cigarette still remains in the package. As a means for containing the imprints of any desired advertising, it is quite important that the container remain servicable throughout the use of a number of cigarette packages. We may find it desirable to use transparent or semi-transparent material for the container to not hide the cigarette imprints on the package adjacent the back face 4 and using the edges for special advertising.

In shipping these cartons in quantity it would become a serious and expensive matter to keep

them in an open condition throughout the time of transportation or storage thereafter. With our improved form of container all these handicaps are overcome and the containers are available at any time. It is immaterial if the overlapping ends of a blank are secured to each other to form an edge of the container or that the overlapping be made on one of the broad faces.

It may be found that certain material will have sufficient resiliency to maintain the corners unbroken even though the container is flattened many times and enough of recuperation to assist in opening the container to receive a package of cigarettes and support a folding booklet of matches.

What we claim is:

A cigarette package container of the class described which comprises a single sheet, integrally attached overlapping ends, a front and a back between the ends forming a collapsible encircling open ended support for a package of cigarettes, a notch at the top and bottom edges of the front, a support for a folding box of matches formed between the notches, and sloping side edges of the notches adapted to easily guide the flap of a folded match book into place between the support and the package of cigarettes.

ALDEN K. CRAWFORD.

HAROLD G. ARNOLD.
